US0D1054405S

(12) **United States Design Patent** (10) **Patent No.:** **US D1,054,405 S**
(45) **Date of Patent:** **** Dec. 17, 2024**

(54) **ANTENNA**

(71) **Applicant:** **Avery Dennison Retail Information Services LLC**, Mentor, OH (US)

(72) **Inventor:** **Antti T. Leskelä**, Vesilahti (FI)

(73) **Assignee:** **Avery Dennison Retail Information Services LLC**, Mentor, OH (US)

(**) **Term:** **15 Years**

(21) **Appl. No.:** **29/873,264**

(22) **Filed:** **Mar. 29, 2023**

(51) **LOC (14) Cl.** **14-03**

(52) **U.S. Cl.**

USPC **D14/230**

(58) **Field of Classification Search**

USPC D14/230, 231-240, 238.1, 299, 343, 489, D14/492, 138, 135; D13/182; D12/42-43
